DESIGN FOR A LIQUID DISPENSER OR THE LIKE

Samuel J. Kaz, Chicago, Ill.

Application March 2, 1933. Serial No. 47,387

Term of patent 3½ years

To all whom it may concern:

Be it known that I, SAMUEL J. KAZ, a citizen of the United States, residing at Chicago, in the county of Cook and State of Illinois, have invented a new, original, and ornamental Design for a Liquid Dispenser or the like of which the following is a specification, reference being had to the accompanying drawing, forming part thereof.

Fig. 1 is a perspective view of a liquid dispenser showing my new design.

Fig. 2 is a diagrammatic side elevation of a liquid dispenser shown in Fig. 1.

I claim:

The ornamental design for a liquid dispenser or the like, substantially as shown.

SAMUEL J. KAZ.
